UNITED STATES PATENT OFFICE.

ERNEST C. BEAUMONT, OF REVERE, MASSACHUSETTS, ASSIGNOR TO UNITED SHOE MACHINERY COMPANY, OF BOSTON, MASSACHUSETTS, A CORPORATION OF NEW JERSEY.

METHOD OF MAKING PULL-ON DEVICES FOR BOOTS AND SHOES.

1,081,924.

Specification of Letters Patent.

Patented Dec. 16, 1913.

Application filed September 17, 1913. Serial No. 790,356.

To all whom it may concern:

Be it known that I, ERNEST C. BEAUMONT, a citizen of the United States, and a resident of Revere, in the county of Suffolk and State 5 of Massachusetts, have invented an Improvement in Methods of Making Pull-On Devices for Boots and Shoes, (Case C,) of which the following description, in connection with the accompanying drawings, is a 10 specification, like characters on the drawings representing like parts.

This invention relates to the method of making pull-on devices for boots and shoes.

In order that the principle of the invention may readily be understood, I shall proceed to describe the best mode known to me for carrying the method of my invention into effect.

In the drawings: Figure 1 is a vertical 20 sectional view of a pull-on device made in accordance with my invention and secured in place. Fig. 2 is a perspective view of a strip which may be employed in the manufacture of the core piece or filler. Fig. 3 is a perspective view of the core piece or 25 filler. Fig. 4 is a plan view, partially broken away, representing a step in the application of the covering strap to the core piece. Fig. 5 is a vertical sectional view thereof. Fig. 6 represents a further step in such 30 application; and Fig. 7 represents the pull-on device ready for application to the boot or shoe, save for the securing of the free end of the strap to the flat edge of the core piece.

Heretofore, shoe-pulls have commonly 35 been made as straps composed of webbing and formed into loops large enough to receive a finger of the user, the end of the strap being attached to the shoe upper. Such a 40 loop-like strap projects a considerable distance above the top of the shoe upper when in use, and after the shoe has been worn a short time, it becomes distorted, usually being bent downward on the outside of the 45 shoe, and in both instances it is unsightly and objectionable, and particularly so in high priced shoes.

The method of my invention has for its 50 object to provide boots and shoes with an improved form of pull-on device which is neat, attractive and highly efficient, and which in the represented embodiment thereof does not project above the shoe, and retains its original form after long use.

I have herein represented one form or 55 embodiment of pull-on device constructed in accordance with my invention, but it will be understood that the pull-on device may be of varying form.

The pull-on device herein represented as 60 the product of my invention is made as a tab instead of a loop, and has an enlarged end portion adapting it to be grasped by the fingers or finger and thumb in drawing the 65 shoe onto the foot. In the form herein illustrated, I have represented the strap, which may be of leather, cloth or other suitable material, and carry the same around and secure it to a core piece or filler by cement or other means, said strap serving as a covering strip for the core piece, and having 70 one end extended beyond said core piece for attachment to the shoe upper. The core piece or filler may be, and preferably is, substantially triangular or wedge-shaped in 75 cross section, and may have unequal length sides, admitting of one of the sides occupying a substantially vertical position against the outer face of the shoe upper at or adjacent the top thereof, another side occupying a substantially horizontal position at or adjacent the top of the upper, and the remaining side occupying a diagonal position as shown. As the covering strap conforms to the contour of the core piece or 80 filler, the device will have an enlarged end portion adapted to be firmly grasped, the thumb or a finger being applied to the inner surface of the shoe upper, and a finger being applied to the outer surface of the pull- 85 on device.

Referring to the drawings wherein I have 90 illustrated the product of my method, 1 represents a shoe upper of any suitable or desired construction. The upper, 1, has a pull-on device attached thereto by stitches or other means, and is preferably provided with a lining, 2. Said pull-on device consists of a core piece or filler, 3, and a covering strap, 4, carried around said core piece 95 and having a free end portion, 5, for attachment to the upper by one or more lines of stitching, 6, which preferably pass through the lining, and the lower one of which preferably passes through the lower end or apex 100 of the pull-on device.

The core piece, 3, may be composed of sole leather or other material of substantial

thickness and is preferably triangular or wedge-shaped in cross section, so that when in use, its inner side may be substantially vertical.

5 The pull-on device does not extend above the upper edge of the upper, or but a very slight distance thereabove.

In order, economically to manufacture pull-on devices in accordance with my invention, I provide a plurality of straps, 7, represented in Fig. 4, each being of the proper width and length to provide a single pull-on device strap. I secure by cement or otherwise the said straps to a blank core piece or filler, 8. As a simple method of making said core piece blank, I may take a long strip of sole leather, as represented at 10, in Fig. 2, wherein it is shown as of quadrilateral form in cross section, and in such case I preferably sever the strip longitudinally, the line of severance being diagonal and extending from one upper corner to the opposite lower corner of the strip, as represented at 11 in Fig. 2, thus forming two wedge-shaped strips, one of which is represented at 8 in Fig. 3. The said long core piece 8 is then applied to the series of straps, 7, preferably at the upper edge thereof, as represented in Figs. 4 and 5, and is then secured thereto by cement or otherwise. In order to hold the free ends of the straps in position, I may cement or paste or otherwise secure a strip of paper, 9, along the inner faces of said straps. The straps are then folded about the long core piece, 8, as represented in Figs. 6 and 7, the free end, 5, being brought down onto the broad end of the core piece, as represented in Fig. 1, and preferably cemented thereto. I thus provide a blank of a suitable size to constitute a series of pull-on devices. I then, in any suitable manner, sever the elongated core strip between the several straps, so as to provide a number of pull-on devices which will then be attached to boots or shoes as indicated in Fig. 1.

Obviously, the elongated core piece may be so applied as to provide two free ends of the strap, both of which may be secured at 50 the inner face of the upper, but which is generally unnecessary.

It will be observed that by employing small strap pieces, I may utilize pieces of scrap which otherwise would not be available.

Instead of applying the cement or adhesive or securing means before the severing operation, it may be applied afterward; but I prefer to apply the securing means before the blank with its contained elongated core piece or filler is severed into pull-on devices.

The paper or other strip, 9, may be removed after the severing of the device into final shape.

Claims:

1. The method herein described of making pull-on devices for boots and shoes, which comprises providing an elongated core piece, folding a plurality of straps transversely about said core piece side by side, with one end only of each strap projecting from the core piece, for attachment to the shoe upper, and then severing the core piece transversely between the straps.

2. The method herein described of making pull-on devices for boots and shoes, which comprises providing an elongated core piece, securing the same transversely to one end only of each of a series of covering straps, 80 folding said straps about said core piece so that the other end of each strap projects therefrom, for attachment to the shoe uppers, and then severing the core piece transversely between the straps.

3. The method herein described of making pull-on devices for boots and shoes, which comprises providing an elongated core piece, folding and securing a plurality of straps transversely about said core piece side by side, with one end only of each strap projecting from the core piece, for attachment to the shoe uppers, and then severing the core piece transversely between the straps.

4. The method herein described of making pull-on devices for boots and shoes, which comprises providing an elongated core piece, securing the same transversely to one end only of each of a series of covering straps, maintaining said covering straps in alignment, folding said straps about said core piece so that the other end of each strap projects therefrom, for attachment to the shoe upper, and then severing the core piece transversely between the straps.

5. That method of making pull-on devices for boots and shoes which comprises severing a strip of quadrilateral cross section longitudinally to form two core strip pieces of triangular cross section, folding a plurality of straps transversely about one of said core strip pieces side by side, with one end only of each strap projecting from the core strip piece, for attachment to the shoe upper, and then severing the core strip piece 110 transversely between the straps.

In testimony whereof, I have signed my name to this specification, in the presence of two subscribing witnesses.

ERNEST C. BEAUMONT.
